LAWN SPRINKLER BASE

Frederick David Chapman, Chicago, Ill., assignor to Scovill Manufacturing Company, Waterbury, Conn., a corporation of Connecticut

Application January 10, 1958, Serial No. 49,199

Term of patent 7 years

(Cl. D91—1)

Fig. 1

Fig. 2

Fig. 4

Fig. 1 is a perspective view of a lawn sprinkler base showing my new design.

Fig. 2 is a front end view thereof.

Fig. 3 is a side end view thereof, and
Fig. 4 is a top plan view thereof.

I claim:

The ornamental design for a lawn sprinkler base, substantially as shown.
